United States Patent Office.

DANIEL C. COLBY, OF WASHINGTON, DISTRICT OF COLUMBIA, ASSIGNOR
TO JOSIAH HUMPHERY, OF SAME PLACE.

Letters Patent No. 77,358, dated April 28, 1868.

IMPROVED DUST-PAN.

The Schedule referred to in these Letters Patent and making part of the same.

TO WHOM IT MAY CONCERN:

Be it known that I, DANIEL C. COLBY, of the city of Washington, District of Columbia, have invented new and useful Improvements in Dust-Pans; and I do hereby declare the following to be a full and exact description of the same, reference being had to the drawings that accompany and form a part of these specifications, in which—

Figure 1 is a view of the pan open, as it lies on the floor when used.

Figure 2, view of the pan after the dust has been swept in and the pan closed.

Letter A represents the body of the pan.

Letter B, a plain metal sheet, and hung with hinges at *e e*, and so arranged that it will form the incline, whose lower edge, *i*, will always rest on the floor when the pan is receiving the dust from the action of the broom, and also to form the cover, as in fig. 2.

C is the handle, and has a ring at its outer end, by which to hang up the pan.

The object of my invention is to provide a dust-pan that shall require no holding while the dust is being swept in, and one that may with greater convenience be carried away to be emptied without having the dust spilled or blown out by passing currents of air.

The first of these is secured by hanging the part B on hinges, as illustrated in the drawings, so that whatever inequalities, such as seams in the carpet, or the like there may be, it will be free to turn on the said hinges, and thus bring the lower or outer edge *i* in contact with the floor or carpet.

The second follows readily by making the main or box part, A, and the part B, such, as to width, that the latter may form a proper cover to the former.

This device gives an article of much greater utility and convenience than dust-pans as heretofore constructed, as the awkward position of stooping to hold the pan while wielding the broom is entirely avoided.

Moreover, as it is always, when on the floor, ready or in position to receive the sweepings, any little gatherings of the broom may be often swept into it, as the room is gone over, and thus much less fine dust raised in the air than ordinarily, as the stooping before mentioned is so disagreeable that it is customary to go over all the room seeking to gather all the sweepings into one place before the pan is used at all.

Still further, being covered by the part B, brought over, as in fig. 2, it can be taken in hand with broom, brush, or pail, and be brought from the upper chambers, and carried away to be emptied without danger of having the dust spilled or blown away in passing through doors or windy places.

Pans like this occupy much less space on the wall when hung up, and pack much better for transportation.

These pans may be made of sheet metal, paper properly prepared, or any other suitable material.

What I claim as of my invention, and desire to secure by Letters Patent, is—

A dust-pan, provided with the part B, so arranged as to serve for the incline on which to receive the dust, and also as cover to the box part, A, for the purposes specified and set forth.

In testimony whereof, I have signed my name to this specification in the presence of two subscribing witnesses.

DANIEL C. COLBY.
